DESIGN FOR AN ELECTRIC FAN

Malcolm S. Park, Mount Kisco, N. Y., assignor to
The Singer Manufacturing Company, Eliza-
beth, N. J., a corporation of New Jersey

Application October 27, 1937, Serial No. 72,437

Term of patent 3½ years

To all whom it may concern:

Be it known that I, Malcolm S. Park, a citizen of the United States, residing at Mount Kisco, New York, have invented a new, original, and ornamental Design for an Electric Fan, of which the following is a specification, reference being had to the accompanying drawing, forming a part thereof.

Fig. 1 is a perspective view of an electric fan

showing my new design. Fig. 2 is a side elevation and Fig. 3 is a rear elevation of the fan shown in Fig. 1.

The dominant feature of the design is illustrated in solid lines in the drawing.

I claim:

The ornamental design for an electric fan, as shown and described.

MALCOLM S. PARK.
